(57) **CLAIM**

The ornamental design for a training device for athletes, as shown and described.

DESCRIPTION

FIG. 1 is a front elevational view of a training device for athletes showing my new design;

FIG. 2 is a rear elevational view thereof;

FIG. 3 is a side elevational view thereof;

FIG. 4 is a top plan view thereof;

FIG. 5 is a bottom plan view thereof;

FIG. 6 is a perspective view thereof; and,

FIG. 7 is a perspective view showing the design in an alternate position.
